UNITED STATES PATENT OFFICE.

HENRY S. CROOKE, OF NEW YORK, N. Y.

SIGN.

SPECIFICATION forming part of Letters Patent No. 258,896, dated June 6, 1882.

Application filed April 1, 1881. (No model.)

To all whom it may concern:

Be it known that I, HENRY S. CROOKE, a citizen of the United States, residing in the city of New York, county of New York, and State of New York, have invented certain new and useful Improvements in Signs, fully described and represented in the following specification and the accompanying drawings, forming a part of the same.

- 10 The object of this invention is the production of an ornamental sign from metal foil. As is well understood, commercial tin-foil consists of a lamina or very thin plate of the metal, which is usually produced by reducing 15 a body of the same by a rolling operation accomplished by pressure-rollers. The product is a thin limp sheet of ductile metal having a highly bright or polished surface, which, by the embossing operation, is rendered highly ornamental. Such an article of commerce is provided with a highly artistic surface, well adapted by reason of its beauty as the foundation surface or mat of a sign; and since such 20 material is well adapted to display brilliant colors upon its surface, and as it is desirable that the letters or other ornamentation constituting a sign shall be as brilliant and lustrous as it is possible to make them, I have devised a mode of combining with ordinary 25 rolled metal foil letters and other ornamental designs formed out of colored foil, which designs are combined with the sheets of foil constituting the base of the sign by simple pressure, the result of which is that the metal 30 composing the ornamental design is united to that composing the base, so as to produce a single homogeneous sheet, upon which the designs appear in the lustrous metallic color possessed by the colored foil.
- 35 To facilitate an understanding of the mode followed in producing these signs, I have illustrated in the accompanying drawings, by Figure 1, a stencil-plate supposed to be made of a sheet of rigid material, in which a design 40 consisting of the letters forming the word "Care" is delineated by removing portions of the body of said plate. In Fig. 2 I have illustrated a sheet of colored foil supposed to be mounted upon a sheet of paper, the body 45 of which foil has been divided by lines that

follow the said design "Care," which dividing of the foil is supposed to have been accomplished by laying the stencil-plate, Fig. 1, over the sheet of foil and using a needle or other sharp instrument to cut the foil by following 55 the border edges of the design in the stencil-plate. Fig. 3 illustrates the condition of the sheet of foil, Fig. 2, when the portions of the foil embraced by the border-lines of the design have been removed. Fig. 4 illustrates 60 the foil with design removed, as in Fig. 3, after having been placed over another sheet of foil and the two consolidated by pressure; and Fig. 5 illustrates an enlarged sectional elevation of Fig. 4, to show the relative positions 65 of the two layers of foil to each other.

In carrying out this invention in its most economic manner I take a sheet, as 2, of common tin-foil, having its surface coated with any desired metallic color, which is slightly 70 secured to a sheet, as 3—say of paper—to the surface of which it will only be temporarily held by the use of ordinary paste. After the same is dry I lay over such sheet of foil 2 a stencil-plate, as 4, containing the design desired to 75 be produced, and with a needle or other sharp instrument I cut the design through said foil, following the outlines of the ornamental design in said stencil-plate. I then remove that portion of the design embraced by the cut 80 lines, as in Fig. 3, and then detach the sheet of foil 2 from the sheet of paper, 3, which sheet 2 will then be a reproduction of the stencil-plate, and laying the sheet of foil now provided with the ornamentation upon a sheet of 85 plain or any color of foil, I pass the two sheets, of foil between pressure-rollers, whereby said sheets are pressed together or combined by adhesion of their contact-surfaces as one homogeneous mass, the design produced by the 90 holes in one sheet being filled or covered by the foil of the other sheet, thus making a single continuous sheet of foil, portions of which contain the design in a contrasting color of foil, the whole being a single homogeneous 95 sheet of metal, which may be attached to or mounted upon any supporting-base for use as a sign. In passing the same through the pressing-rollers any surface finish desired may be imparted to the foil by embossing, frosting, 100

ormatting, according to the processes set forth in Letters Patent Nos. 227,495, 227,496, and 229,677.

It is obvious that the letters or other designs removed from the colored foil may be laid upon the surface of the plain sheet of foil, if desired, and the two consolidated and caused to adhere by the pressing operation; but it will be apparent that this mode necessitates nice adjustment of the parts and great care in the operation, and would be difficult, therefore, to perform with that cheapness necessitated by the low price at which these signs must be sold. The various parts of the ornamental design may thus be produced in different colors, and the groundwork or supporting-layer of the foil may have its usual metal surface or be coated with one or more colors in various parts, as fancy may dictate or occasion require. In all cases, however, the ornamentation appearing in colors that properly contrast or blend with the supporting-layer of foil.

What is claimed is—

1. A sign composed of separate and contrasting pieces of tin-foil united to form a homogeneous sheet, and having portions removed from one of the pieces so as to disclose the other, substantially as described. 25

2. The method of forming signs by removing ornamental shapes or portions from a sheet of tin-foil and then covering the openings formed by said removed portions with a separate sheet of foil, and uniting the two to form a single homogeneous sheet, substantially as described. 30

In testimony whereof I have hereunto set my hand in the presence of two subscribing witnesses.

HENRY S. CROOKE.
